UNITED STATES PATENT OFFICE.

ROBERT D. McMANIGAL, OF LOGAN, OHIO, ASSIGNOR TO THE McMANIGAL GRATELESS FURNACE COMPANY, OF COLUMBUS, OHIO.

FURNACE.

1,081,545.

Specification of Letters Patent.

Patented Dec. 16, 1913.

Application filed September 26, 1912. Serial No. 722,460.

To all whom it may concern:

Be it known that I, ROBERT D. McMANIGAL, a citizen of the United States, residing at Logan, in the county of Hocking and 5 State of Ohio, have invented certain new and useful Improvements in Furnaces; and I do declare the following to be a full, clear, and exact description of the invention, such as will enable other skilled in the art to 10 which it appertains to make and use the same.

This invention relates to improvements in furnaces.

One object of the invention is to provide 15 a furnace having a fire box constructed and arranged in such manner as to obviate the use of a grate.

Another object is to provide a furnace 20 having an improved construction and arrangement of coking chamber and means whereby the volatile gases produced by the coking of the coal therein as well as the products of combustion from the fire will be entirely consumed and the heat from these 25 burning products utilized with the heat from the burning fuel for heating the furnace.

A further object is to provide a furnace of 30 the character described having an improved arrangement of ventilating passages whereby air is supplied to the burning fuel in the fire box thus insuring a perfect combustion of the fuel.

With these and other objects in view, the 35 invention consists of certain novel features of construction, combination and arrangement of parts as will be more fully described and claimed.

In the accompanying drawings;

40 Figure 1 is a vertical longitudinal section of my improved furnace as applied to a tubular boiler; Fig. 2 is a horizontal sectional view taken above the coking chamber of the furnace and on a line 2-2 of Fig. 1; 45 Fig. 3 is partly a front end elevation and partly a vertical cross section of the furnace; Fig. 4 is a vertical cross section taken on the line 4-4 of Fig. 1; Fig. 5 is a horizontal sectional view taken through the wall 50 separating the coking chamber from the ash pit showing more clearly the flues formed therein.

In the present embodiment of the invention wherein the same is shown as being 55 applied to a tubular boiler 1 denotes the fur-

nace and 2 denotes the boiler the forward end of which communicates with the smoke box 3 which communicates at its upper end with the stack 4 in the usual or any suitable manner. In the front end of the furnace 60 which in the present instance is built of masonry is arranged the fire box 5 the rear or bridge wall 6 of which extends upwardly to within a short distance from the bottom of the boiler and the upper end of the bridge 65 wall is of openwork construction or provided with a series of vertical and horizontal longitudinal passages 7 through which the flame and heat passes and is divided and spread out over the lower surface of the 70 boiler thus effectually increasing the heating capacity of the fire.

The lower end of the fire box 5 communicates with ash pits 8 which extend to the front end of the furnace and are provided 75 with clean-out doors 9 through which the ashes may be removed when necessary. The doors 9 are provided with suitable draft dampers 10 as shown. The upper portion of the fire box 5 also communicates with 80 coking chambers 11 which extend to the front end of the furnace and are provided with doors 12 through which fresh fuel is supplied to the furnace. The doors 12 are also provided with suitable dampers 13 as 85 shown. In the horizontal division wall 13' between the ash pits and the coking chambers are arranged a series of longitudinally disposed draft passages 14 which open through the front end of the furnace and 90 communicate at their rear ends with the fire box as shown.

Any suitable number of draft passages 14 may be provided and said passages are preferably closed at their forward ends by doors 95 15 having arranged therein suitable dampers 16 whereby the draft through the passages 14 to the fire box may be controlled. By providing the passages 14 it will be seen that a perfect ventilation may be provided 100 for the fire box and the burning fuel therein supplied with a sufficient quantity of air to cause the same to burn freely and to produce a perfect combustion of the fuel.

The tops of the ash pits and coking chambers are preferably arch shaped and the arch shaped tops of the coking chambers are extended back beyond the inner side of the front wall of the furnace and over a considerable portion of the fire box as clearly 105 110

shown at 17 in Fig. 1 of the drawings and in the extended arched tops 17 of the coking chambers are series of vertically and radially disposed passages 18 through which the volatile gases arising from the coking coal in the coking chambers passes and commingles with the smoke and products of combustion from the burning fuel in the fire box. Formed in the front wall of the furnace immediately above the coking chambers are a series of horizontal longitudinally disposed air passages 19 the inner ends of which communicate with the space above the extended arched tops 17 of the coking chambers and the outer ends of which are provided with doors 20 having suitable dampers 21 whereby the currents of air through the passages 19 are controlled. The air entering through the passages 19 mixes with the combined gases and products of combustion from the coking chambers and fire box and forms a highly combustible gas which burns freely and is entirely consumed in the space above the fire box and the heat from this burning gas is thus utilized with the heat from the burning fuel for heating the boiler. By arranging the bridge wall of the furnace and extending the arched tops of the coking chambers back over the fire box in the manner described, it will be seen that the space above the tops of the coking chambers and below the boiler forms practically a mixing chamber for the gases and products of combustion where these gases and products together with the air supply entering through the passages 19 is combined in the proper proportions for burning freely thus producing a smokeless as well as a grateless furnace.

While I have herein shown and described the furnace as being provided with two coking chambers and ash pits I do not desire to be understood as limiting the structure of the furnace to any particular number of coking chambers or ash pits as it is obvious that I may provide any desired number of chambers and ash pits and that any suitable number of air passages 19 may also be provided.

It will also be understood that while I have herein shown and described the invention as applied to a boiler furnace it will be obvious that the same may be applied to any form of furnace or kiln.

Having thus described my invention, what I claim is:

The combination with a coking chamber and ash pit of a furnace, of a division wall separating the same and provided with a longitudinal draft passage open to the atmosphere, an arch also provided with a longitudinal draft passage leading therethrough, an upstanding bridge wall located in rear of the coking chamber and arch and separated from the rear end of the division wall, the upper end of the upstanding wall being provided with vertical and horizontally arranged passages for the purposes described.

In testimony whereof I have hereunto set my hand in presence of two subscribing witnesses.

ROBERT D. McMANIGAL.
